UNITED STATES PATENT OFFICE.

OTTO BALOGH, OF CHICAGO, ILLINOIS, ASSIGNOR OF ONE-HALF TO
ABRAHAM MARGOLIS, OF SAME PLACE.

DESIGN FOR A STOOL.

SPECIFICATION forming part of **Design No. 31,759**, dated **October 31, 1899**.

Application filed April 12, 1899. Serial No. 712,808. Term of patent 31 years.

To all whom it may concern:

Be it known that I, OTTO BALOGH, a citizen of the United States, residing at Chicago, in the county of Cook, State of Illinois, have invented and produced a new and original Design for a Stool, of which the following is a description, reference being had to the accompanying drawing, which forms a part of this application, and in which the figure is a perspective view of my design for a stool.

My design for a stool consists of a box in octagonal form A, the lower edge of which is bound by a ruffle 2^a and the top by a cush-

ioned cover B. At the upper portion of the angles formed by the eight flat sides are ornamental pieces 1^a.

Having thus described my invention, what I claim is—

The design for a stool, substantially as herein shown and described.

In testimony whereof I affix my signature in presence of two witnesses.

OTTO BALOGH.
